his Attorney.

UNITED STATES PATENT OFFICE.

WILLIBALD TRINKS, OF PITTSBURGH, PENNSYLVANIA, ASSIGNOR, BY MESNE ASSIGNMENTS, TO NATIONAL BRUSH WASHING MACHINE COMPANY, OF PITTSBURGH, PENNSYLVANIA, A CORPORATION OF DELAWARE.

ROLL CONSTRUCTION.

1,190,689.

Specification of Letters Patent.

Patented July 11, 1916.

Original application filed September 28, 1915, Serial No. 53,004. Divided and this application filed March 3, 1916. Serial No. 81,823.

To all whom it may concern:

Be it known that I, WILLIBALD TRINKS, a citizen of the United States, and residing in the city of Pittsburgh, in the county of Allegheny and State of Pennsylvania, have invented or discovered new and useful Improvements in Roll Construction, of which the following is a specification.

My invention consists in a new and improved roll construction especially intended for the backing or tension rolls of rotary-brush washing machines, and similar purposes.

This patent application is a division of my pending patent application for "Improvements in washing machines", filed September 28, 1915, Serial Number 53,004.

The object in view is the provision of a light weight, inexpensive and durable roll which is water-tight, presents an unyielding and unindentable perimetral surface and which will not sag, buckle or bend from use. To accomplish these purposes, I provide a roll structure comprising an outer metal cylinder, preferably of non-corrosive material, such as brass, and an internal reinforcement for said cylinder consisting of an expandible cylindrical socket member having slotted walls and a plug member driven into said socket member to expand the latter into snug supporting contact with the said metal cylinder. To prevent the entrance of water, the ends of said cylinder are closed with end members.

Novel features of construction and arrangement of parts will appear from the following description.

In the accompanying drawings, Figure 1 is a longitudinal section of my improved roll; Fig. 2 is an end view of the socket member; Fig. 3 is a sectional view taken along the line III—III in Fig. 1; Fig. 4 is a similar view taken along the line IV—IV in Fig. 1, and Fig. 5 is a side elevation of the plug.

The following is a detailed description of the drawings.

1 is a cylinder of suitable hard, non-corrosive metal, such as drawn brass. Said cylinder 1 is braced and supported by internal reinforcement composed of interlocking members 2 and 3, preferably of wood.

2 is a hollow socket member having a cy-

lindrical outer wall which fits loosely in the cylinder 1. The bore of said socket member is preferably tapered from one end to the other, as shown. The wall of said socket member is provided with a pair of diametrically opposed slots *a* extending from a point adjacent to one end of the socket to the other end of the same, while 90 degrees from the slots *a* are a pair of similar slots *b* which extend from a point adjacent to the last named end of the socket to the first named end of the same. The length of the socket 2 is less than that of the cylinder 1.

3 is the frusto-conical plug adapted to enter the socket 2 and expand the same against the cylinder 1.

The socket 2 is first inserted into the cylinder 1 and is properly centered and held stationary while the plug 3 is driven into its bore, expanding the socket into snug contact with the cylinder 1, thereby supporting and reinforcing the latter. The ends of the cylinder 1 are closed by members 4 turned from brass castings or otherwise formed of some non-corrosive material. Journal studs 5 or other means for mounting the roll, extending outwardly axially of the ends 4, may be provided. The end members 4 are each provided with an annular perimetral surface 6 which fits snugly into the open end of the cylinder 1 and is sweated in place with soft solder. A radial flange 7 is also provided on the member 4, which abuts against the end of the cylinder 1.

It is evident that my improved roll will present a hard, unindentable working surface; that it will not sag, bend or buckle, and that water and filth are completely excluded from its interior.

What I desire to claim is:

1. A roll structure comprising an outer metal cylinder and an internal reinforcement for the same consisting of an integral expandible cylindrical socket member having longitudinally slotted walls and a tapered plug member driven into said socket member to expand the latter against said cylinder, for the purpose described.

2. A roll structure comprising an outer metal cylinder and an internal reinforcement for the same consisting of an expandible cylindrical socket member having lon-

gitudinal slots in its wall extending alternately from either end and a tapered plug member driven into said socket member to expand the latter against said cylinder, for the purpose described.

3. A roll structure comprising an outer metal cylinder, an internal reinforcement for said cylinder consisting of an expandible socket member having its wall slotted longitudinally alternately from either end and a tapered plug member driven into said socket member to expand the latter against said cylinder, and end members tightly closing the ends of said cylinder, for the purpose described.

4. A roll structure comprising an outer metal cylinder, an internal reinforcement for said cylinder consisting of an expandible socket member having longitudinal slots in its wall extending alternately from either end and a tapered bore and a tapered plug member driven into said bore to expand said socket member against said cylinder, and end members inserted into and tightly closing the end of said cylinder, for the purpose described.

Signed at Pittsburgh, Pa., this 29th day of November, 1915.

WILLIBALD TRINKS.
